METHOD OF SEALING METALLIC CLOSURES FOR BOTTLES

Carl Paul Sorensen, Chicago, Ill., assignor of one-half to Joseph B. Lindecker, Skokie, Ill.

Application May 4, 1953, Serial No. 352,740

10 Claims. (Cl. 219—85)

My invention relates preferably to metallic bottle closures and to the apparatus and method of sealing the same upon a bottle.

The method of my invention has a number of characteristics. Generally speaking, it consists in placing a metallic skirted closure over the mouth of the bottle and about the exterior bottle portions adjacent the bottle mouth, placing a metallic strand or metallic ring about the skirt of the metallic closure, contracting the ring into tight engagement with the metallic closure by relatively moving adjacent portions oppositely and circumferentially, placing a bond between said metal ring contacting portions that is inclusive of fusible metal that will fuse in response to heat, applying sufficient heat by the application of fusing currents of electricity to the region of said ring portions and bond to cause the fusible metal to fuse, and permitting the fusible metal to harden while the ring is contracted to hold said ring contacting portions in ring contracting relation. In the method, as preferably practiced, the metal ring is of such circumferential length that the adjacent portions thereof that are oppositely and circumferentially moved to contract the ring are brought into mutually side by side lapping relation so that they may be merely torn apart when the closure is to be removed to afford access to the bottle covered by the closure. The fusible metal is desirably provided directly upon these ring portions whereby the ring, itself, is inclusive of a constituent which will fuse in response to heat. The closures are formed of non-combustible material, such as metallic foil, or a lamination having foil on the outside thereof, and the mutually lapping portions of the metal rings are preferably tin and lead coated so as to be readily fused by heat.

In the preferred way of practicing the method of my invention, the necessary heat is furnished by an electric current of suitable volume and pressure, passed through a portion of the ring, the ring being preferably metallic, and also through the tin and lead coating thereon, this tin and lead coating constituting the preferred form of fusible cement that is adaptable to fuse in response to heat.

In previous methods of sealing bottles by electric current and a coated metallic wire, the closures were formed of combustible material, such as paper, or material which would not conduct electric current. Said methods in some localities are objectionable because of the need for sealing bottles with metal closures, and employing metallic coated wire and electricity to seal the wire about the closure. Said previous methods, for instance are shown in Letters Patents of the United States: No. 1,635,510; No. 1,635,515 and 2,011,142. Another objection to said previous methods has been the objectional types of electric switches used without suitable means to safe-guard the complementary contacts of the switch against the effect of sparking, as shown by Patent No. 1,958,685 of 1934.

The bottle about which the closure is placed is generally externally enlarged at its mouth. In the structure

2

of my invention, the ring is placed around the closure and the external bead portions of the bottle mouth, or below said bead portions and about the closure skirt, and has mutually side by side lapping wire portions that are united by a fusible metal bond that holds these wire portions in ring contracting relation and permits these portions to be readily torn apart when the bottle is to be uncovered, at least one of the mutually lapping portions having an unattached end which may be grasped for this purpose. While this fusible metal cement seal is preferably applied or employed in accordance with the method of my invention, yet the structure of my invention is not to be limited to its production by my method nor is the method to be limited to the production of the structure of my invention. The ring is preferably formed of non-resilient metal wire so that it will not spring back into shape, in case of its enlargement by a tool in an effort to effect an unauthorized removal of the bottle closure. The external bead of the bottle mouth may be provided with an inwardly extending groove, or the enlarged external bead itself in the region of its mouth can be used to prevent the withdrawal of the ring over the bottle mouth, in case removal of the bottle closure is sought without breaking the cement bond.

The method and structure of my invention will be more fully explained in connection with the accompanying drawing in which

Fig. 1 is a perspective view of a bottle with a metallic closure assembled therewith;

Fig. 2 is a sectional view on line 2—2 of Fig. 1;

Fig. 3 is a sectional view similar to Fig. 2, where a laminated closure is employed;

Fig. 4 is a front view of a portion of the bottle in the zone of the ring, the mutually lapping portions of the ring being shown in section in order to illustrate the tin and lead coatings thereon;

Fig. 5 is a diagram illustrating a circuit upon the mutually lapping portions of the ring so that it may be heated to fuse the bond for uniting the lapping ring portions;

Fig. 6 is a sectional view showing a closure sealed upon a bottle where the bead portion of the bottle has an annular groove therein;

Fig. 7 is a diagram illustrating an electric circuit and arrangement of mechanical parts whereby the fusible metal coating upon the mutually lapping portions of the ring may be heated to fuse the same for the purpose of uniting these mutually lapping ring portions while they are in ring contracting relation while in contact with a metallic closure.

Fig. 8 is a diagram illustrating an electric switch and an electric circuit connected therewith and showing specifically a front elevation of the switch with arms, cams, and contact points provided with spark quenching capacitors.

Fig. 9 is a circuit diagram illustrating one use to which the invention may be put, the switch, the capacitors, the transformer, the rheostat and welding points being included with the diagram.

The bottle 1, illustrated, is one which is commonly employed for containing milk or cream. It has an external enlargement or surrounding bead 2 at the mouth of the bottle. A metallic closure 4, preferably aluminum, or a laminated closure having an inner layer of paper 3 and an outer layer of aluminum foil 5, is placed over the mouth of the bottle, this metallic closure 4 having a skirt 6 integral therewith which is encircled by a ring 7, preferably formed of non-resilient metal, this ring having mutually lapping circumferentially extending portions 8 and 9. A fusible metal bond 10 is disposed between said

mutually lapping and circumferentially extending ring portions and serves to hold these portions in assembly, the bond being brought into its holding relation after the ring portions 8 and 9 have been drawn circumferentially and in opposite directions with sufficient force to tightly hold the closure skirt against the neck or bead portion of the bottle.

The closure employed is preferably formed from metallic foil, and preformed to the shape of the closure disclosed in Patent No. 1,635,510, dated July 12, 1927. Such an aluminum closure permits the ring to be tightly placed into its skirt whereby the closure may have effective and sealing engagement with the bottle bead or the neck portion thereof. The mutually lapping portions of the ring desirably terminate in free ends 8' and 9', 9' which may be grasped by the fingers of one's hand in order that the mutually lapping ring portions may be torn apart when the bottle closure is to be removed. One of the free end portions 8' or 9', say the portion 9', is desirably sufficiently long so that it may be grasped by the thumb and finger when the bond or seal is to be broken. The two ring portions are desirably so related that one portion, say the portion 8, is above the other so that both may take part in gripping the closure without imposing undue strain upon the fusible metal bond 10 between the mutually lapping ring portions.

The wire of the ring is tinned with lead, the tin and lead coating of the ring wire fusing under a degree of heat. The heat for fusing the tin and lead coating upon the mutually lapping portions of the ring may be furnished by a transformer of primary voltage suitable to input voltage, preferably used with 110 volt, or 220 volt electric lines, the transformer in turn supplying suitable transformed secondary current of low voltage through a rheostat to the welding fingers, the function and operation of which will be described later. The current from the transformer is desirably applied while the mutually lapping portions of the ring are tightly drawn circumferentially of the bottle bead or the bottle neck and in opposite directions and to an extent sufficient to contract the ring, as desired. When the current has caused the tin and lead coatings upon the mutually lapping portions of the ring to fuse, the circuit is opened and the tin and lead coating is allowed to harden while the ring is contracted, the lead thereafter holding the mutually lapping ring portions in contracting relation. As illustrated in Fig. 5, the terminals 12 and 13 of the electric circuit are preferably applied to the ring in a manner to include both mutually lapping ring portions directly therebetween. When the necessary fusing has been effected, the terminals 12 and 13 may be removed or the circuit may be opened by the cam operated switch 14, as desired.

The switch 14 illustrated clearly by Figure 8, has an arm 15 which pivots at 16, between its ends. This arm 15 bears, at one end, upon a cam 18, being pressed against the surface of the cam by a spring 19 which is anchored at one end upon an insulating mounting block 20 and is attached at its other end to a finger 21 that projects angularly from said arm 15. This cam 18 as illustrated is automatically turned by mechanical means, not shown. Said arm 15 is connected with an electric conductor 22. Said arm 15 is enlarged at its lower end and there carries a contact post 23, with a contacting surface 24 of highly refractory conducting material, such as tungsten. I provide a contact post 25 with surface 26 that is complementary to and engageable with said post 23 and surface 24. Said post 25 is mounted upon a leaf spring 27 connected with a metallic bracket 28, having an electric conductor 29 connected thereto. During each revolution of the cam 18, the switch arm 15 is brought into and out of circuit closing adjustment as will be apparent by an inspection of Figures 8 and 9. Whenever the circuit is closed the electric current is brought into and out of cir-

cuit. The leaf spring 27 is under such tension that it will follow the circuit opening movement of the switch member arm 15 until it is individually arrested in this following movement by a stop 17. Arcing is prevented from occurring between the contacting point surfaces 24 and 26 by the installing of a pair of capacitors 30 and 31 connected in series and shunt connected across conductors 22 and 29; that is the capacitors are connected by one wire to the electric source or wire 22, and by a second wire to the conductor 29 which is connected to one terminal of the transformer 32. Said capacitors are preferably made to handle 110 volts or 220 volts and constructed of metal plates or foil rolls as required. The capacitors absorb sparking at contact points 24 and 26 and keep the primary voltage at the same voltage and equal level as required to deliver equal current to the secondary of the transformer, thereby eliminating the adjusting of the heat control of timing switch which would be necessary due to a drop of primary voltage due to an overload of additional machinery etc. on the same electric circuit. An electric capacitor is formed by two conductors or groups of conductors separated by a tape of insulating material which is called dielectric. A capacitor of this type has the function to store up a great amount of electrical energy in an electrostatic form. A capacitor is usually made up of either metal plates or foil rolls and is connected in series, thereby absorbing the spark, or counterforce of the electric circuit and keeping the current up to par at all times. A rheostat 35 is preferably connected in conjunction with the secondary outlet of the transformer 32 to obtain the desired voltage as required for different types of closures and different conditions. The welding tips 12 and 13 are provided, and the tip 12 is connected by a wire 38 to said rheostat 35 and tip 13 is connected by a wire 39 to the highest voltage tap of the secondary winding of the transformer 32. Said tip 13 and wire 39 are mechanically grounded by a No. 8 electric wire, designated here as 40, to the closure applying machine. It will be observed that the welding tip 12 connected in conjunction with the rheostat 35 will remain insulated while the other welding tip 13 in conjunction with the secondary outlet of the transformer is mechanically grounded, as clearly shown by Figures 6, 8 and 9.

Referring especially to Fig. 7, the bottle 1 is shown positioned upon a support 50 and centered by a centering device 41 having an insulation pad 42 positioned therebetween. The wire 7 is wound upon a spool 43 supported by spool holder 44 which is machine grounded. Said wire 7 is guided by roller 45 so it can be applied to the closure positioned upon said bottle. Roller 45 is grounded and works in conjunction with conventional means which turns one and one-half times about the closure as disclosed by Patent No. 1,635,515. The free end of the wire strand is gripped by suitable jaws 46 and 47 which are also machine grounded. The wire is suitably applied to the closure skirt by the rotation of a wire nozzle, not shown. The wire is closely wrapped about the closure skirt so that there is provided a closure contracting ring having mutually lapping portions as described above, it being the mutually lapping portions that are bonded together by fusing the tin and lead coating that is on the wire and allowing the tin and lead coating to hold said lapping portions in ring contracting relation. The free end of the wire extends beyond the seal so it may be grasped to tear the mutually lapping portions of the ring apart when access is to be had to the bottle. The bond between the lapping portions is fused by heat and the heat is furnished by electric current supplied by operating means previously described herein. Mechanism not shown is provided for severing the wire from the continuous strand upon spool 43. After the wire is cut, the seal is completed upon the bottle, the bottle can be removed from the sealing machine thus being the conclusion of the cycle of operations under description.

From the above it is clearly shown that the machine is completely grounded. The metallic closure upon the bottle is insulated from the bottle centering device by insulation means 42. Said insulating means 42 prevents electric welding current from making contact between the top of the metal closure and a machine ground. The wire 39 is connected with the secondary outlet of the transformer and is grounded by wire 40. The wire 38 is connected with the rheostat 35 and the other secondary outlet of the transformer, leaving said parts insulated from machine. Therefore, it is clearly seen that the current carried by the welding points 12 and 13 is not allowed to travel through the metallic closure to the metal parts of the bottle centering device because of insulation pad 42. The fusing current will travel from one welding point to the other only through the mutually lapping portions of the wire as the current always travels through and by the shortest path. In other words the current will travel from the transformer through the rheostat to the welding point 12, then through the mutually lapping portions of the wire 8 and 9 to the welding point 13 and through wires 39 and 40 to a mechanical ground.

It will be observed that the method of my invention is a material improvement upon the prior methods employed for contracting closures holding rings about the skirts of closures made of paper such as disclosed in Patent No. 1,635,510, dated July 12, 1927.

It will also be observed that the electric circuit embodies an improved switch in my novel invention and is a material improvement upon that disclosed in the above stated Patent No. 1,958,685. Novelty appears in many respects among which is the ease with which the ring of my present invention may be applied on a metallic closure by electrical means so that the closure held thereby may be removed easily from the bottle it covers.

I do not wish to be limited to the method and apparatus herein disclosed for producing the product. It is obvious that changes may be made without departing from the invention.

Having thus described my invention, I claim:

1. Method of sealing a bottle which consists in placing a skirted closure of metallic electric current conductive material over the mouth of the bottle and about the bottle neck; placing about the electric current conductive closure skirt and bottle neck a ring consisting of electric current conductive wire coated with fusible metal; contracting the ring by relatively moving adjacent ring portions, oppositely and circumferentially; contacting said adjacent overlapping ring portions with a pair of electric current conductive means; passing sufficient electric current from one of said conductive means connected to a suitable source of electric current to the second of said conductive means secured to a mechanical ground, said electric current traveling through said adjacent ring portions between said pair of conductive means and to said mechanical ground while said pair of conductive means is in contact with said ring portions, said current heating said overlapping portions and contracting portions of the ring to fuse the fusible metal coating thereof while in contact with said electric current conductive closure; and permitting the fused metal to harden while the ring is contracted to hold said ring portions in ring-contracting relation.

2. Method of sealing a bottle which consists in placing a skirted closure of metallic electric current conductive material over the mouth of the bottle; placing about the closure skirt a ring consisting of electric current conductive wire coated with fusible metal; contracting the ring by relatively moving adjacent ring portions, oppositely and circumferentially; contacting said adjacent overlapping ring portions with a pair of electric current conductive means; passing sufficient electric current from one of said conductive means connected to a suitable source of electric current to the second of said conductive means se-

cured to a mechanical ground, said electric current traveling through said adjacent ring portions between said pair of conductive means and to said mechanical ground while said pair of conductive means is in contact with said ring portions, said current heating said overlapping portions and contracting portions of the ring to fuse the fusible metal coating thereof while in contact with the electric current conductive closure; and permitting the fused metal to harden while the ring is contracted to hold said ring portions in ring-contracting relation.

3. Method of sealing a bottle which consists in placing a skirted aluminum electric current conductive closure over the mouth of the bottle and about the bottle neck; placing about the electric current conductive closure skirt

15 and bottle neck a ring consisting of electric current conductive wire coated with fusible metal; contracting the ring by relatively moving adjacent ring portions, oppositely and circumferentially; contacting said adjacent overlapping ring portions with a pair of electric current conductive means; passing sufficient electric current from one of said conductive means connected to a suitable source of electric current to the second of said conductive means secured to a mechanical ground, said electric current traveling through said adjacent ring portions between said

25 pair of conductive means and to said mechanical ground while said pair of conductive means is in contact with said ring portions, said current heating said overlapping portions and contracting portions of the ring to fuse the fusible metal coating thereof; and permitting the fused metal to harden while the ring is contracted to hold said ring portions in ring-contracting relation.

4. Method of sealing a bottle which consists in placing a skirted aluminum electric current conductive closure over the mouth of the bottle; placing about the electric

35 current conductive skirt a ring consisting of electric current conductive wire coated with fusible metal; contracting the ring by relatively moving adjacent ring portions, oppositely and circumferentially; contacting said adjacent ring portions with a pair of electric current conductive means;

40 passing sufficient electric current from one of said conductive means connected to a suitable source of electric current to the second of said conductive means secured to a mechanical ground, said electric current traveling through said adjacent ring portions between

45 said pair of conductive means and to said mechanical ground while said pair of conductive means is in contact with said ring portions, said current heating the overlapping portions and contracting portions of the ring to fuse the fusible metal coating thereof while in contact

50 with said aluminum closure; stopping the flow of current between said welding points and permitting the fused metal to harden while the ring is contracted to hold said ring portions in ring-contracting relation.

5. Method of sealing a bottle which consists in placing

55 a laminated skirted closure embodying an outer layer of metallic electric current conductive material over the mouth of the bottle and about the bottle neck; placing about the closure skirt and bottle neck a ring consisting of electric current conductive wire coated with fusible

60 metal; contracting the ring by relatively moving adjacent ring portions, oppositely and circumferentially; contacting said adjacent ring portions with a pair of electric current welding points; passing sufficient electric current from one of said welding points connected to a suitable source

65 of electric current to the second of said welding points secured to a mechanical ground, said electric current traveling through said adjacent ring portions between said pair of welding points and to said mechanical ground while said pair of welding points is in contact with said

70 ring portions, said current heating the overlapping portions and contracting portions of the ring to fuse the fusible metal coating thereof while said ring is in direct contact with the outer layer of metallic electric conductive closure material; stopping the flow of current be-

75

tween said points; and permitting the fused metal to harden while the ring is contracted to hold said ring portions in ring-contracting relation.

6. Method of sealing a bottle with a laminated closure, comprising an outer layer of metallic electric current conductive material, which consists in placing the closure over the mouth of the bottle and about the bottle portions adjacent to said mouth; placing about the outer layer of said metallic electric current conductive material of said closure a ring consisting of electric current conductive wire coated with fusible material; contracting the ring by relatively moving adjacent ring portions, oppositely and circumferentially; contacting said adjacent ring portions with a pair of electric current welding points; passing sufficient electric current from one of said welding points connected to a suitable source of electric current to the second of said welding points secured to a mechanical ground; said electric current traveling through said adjacent ring portions between said pair of welding points and to said mechanical ground while said pair of welding points is in contact with said ring portions; said current heating the overlapping portions and contacting portions of the ring to fuse the fusible metal coating thereof; stopping the flow of current between said points; and permitting the fused metal to harden while the ring is contracted to hold said ring portions in ring-contracting relation.

7. Method of sealing a bottle which consists in placing a laminated skirted closure embodying an outer layer of metallic electric current conductive material over the mouth of the bottle; placing about the closure skirt a ring consisting of electric current conductive wire coated with fusible metal; contracting the ring by relatively moving adjacent ring portions, oppositely and circumferentially; contacting said adjacent ring portions with a pair of electric current welding points; passing sufficient electric current from one of said welding points connected to a suitable source of electric current to the second of said welding points secured to a mechanical ground; said electric current traveling through said adjacent ring portions between said pair of welding points and to said mechanical ground while said pair of welding points is in contact with said ring portions; said current heating the overlapping portions and contracting portions of the ring, which is the shortest distance for the currents of electricity to travel, thereby fusing the fusible metal coating thereof; stopping the flow of electric current between said points; and permitting the fused metal to harden while the ring is contracted to hold said ring portions in ring-contracting relation.

8. Method of sealing a bottle which consists in placing a laminated skirted closure embodying an outer layer of electric current conductive aluminum over the mouth of the bottle; placing about the closure skirt a ring consisting of electric current conductive wire coated with fusible metal; contracting the ring by relatively moving adjacent ring portions, oppositely and circumferentially; contacting said adjacent ring portions with a pair of electric current welding points; passing sufficient electric current from one of said welding points connected to a suitable source of electric current to the second of said welding points secured to a mechanical ground; said electric current traveling through said adjacent ring portions between said pair of welding points and to said mechanical ground while said pair of welding points is in contact with said ring portions; said current heating the overlapping portions and contracting portions of the ring to fuse the fusible metal coating thereof while the ring is in direct contact with said outer layer of aluminum of said closure; stopping the flow of electric current between the points;

and permitting the fused metal to harden while the ring is contracted to hold said ring portions in ring-contracting relation.

9. Method of sealing a bottle which consists in placing a skirted closure of electric current conductive metallic material over the mouth of the bottle and about the external bead portion of the bottle mouth; placing about the closure skirt and said bead portion of the bottle mouth a ring consisting of electric current conductive wire coated with fusible metal; contracting the ring by relatively moving adjacent ring portions, oppositely and circumferentially; contacting said adjacent ring portions with a pair of electric current welding points; passing sufficient electric current from one of said welding points connected to a suitable source of electric current to the second of said welding points secured to a mechanical ground; said electric current traveling through said adjacent ring portions between said pair of welding points and to said mechanical ground while said pair of welding points is in contact with said ring portions; said current heating the overlapping portions and contracting portions of the ring, which is the shortest distance for the current to travel, to fuse the fusible metal coating thereof; stopping the flow of electric current between the points; and permitting the fused metal to harden while the ring is contracted to hold said ring portions in ring-contracting relation.

10. Method of sealing a bottle which consists in placing a skirted closure of electric current conductive aluminum over the mouth of the bottle and about the external bead portion of the bottle mouth; placing by suitable mechanism a ring about the closure skirt and said bead portion of the bottle mouth, said ring consisting of electric current conductive wire coated with fusible metal; contracting by suitably grounded mechanical means the relatively moving adjacent portions of said ring, oppositely and circumferentially; insulating portions of the metallic skirted closure from said mechanical means; contacting said adjacent ring portions with a pair of electric current welding points; passing sufficient electric current from one of said welding points connected to a suitable source of electric current to the second of said welding points secured to a mechanical ground; said electric current traveling through said adjacent ring portions between said pair of welding points and to said mechanical ground while said pair of welding points is in contact with said ring portions; said current heating the overlapping portions and contracting portions of the ring to fuse the fusible metal coating thereof, said current traveling over said contacting portions between said points since it is the shortest distance for said current to travel since the closure is insulated from a mechanical ground; stopping the flow of electric current between said points; and permitting the fused metal to harden while the ring is contracted to hold said ring portions in ring-contracting relation.
